TAKE-OFF TOOL FOR WELLS

James G. Phillips, Wink, Tex.

Application January 16, 1939, Serial No. 251,211

4 Claims.

(Cl. 166—1)

This invention relates to new and useful improvements in "take-off" tools for oil, gas and water wells.

One object of the invention is to provide a take-off tool employing the usual left-hand threads and being so constructed as to be operable at any desired time.

Another object of the invention is to provide a ball-bearing take-off tool so constructed as to retain the weight of the string of tubing upon said ball-bearings, thereby leaving the thread connections free to turn.

Still another object of the invention is to provide a ball-bearing take-off tool operating through ground joints and oil baths thereby positively eliminating foreign substances from interfering with connecting screw threads.

The invention will be more readily understood from a reading of the following specification and by reference to the accompanying drawing wherein means for carrying out the invention are disclosed and wherein:

Figure 1 is a transverse vertical sectional view of a take-off tool constructed in accordance with the present invention.

Figure 2 is a horizontal cross-sectional view taken on the lines 2—2 of Figure 1.

Figure 3 is another horizontal cross-sectional view taken on the line 3—3 of Figure 1, and

Figure 4 is a transverse vertical sectional view of a modified form of the invention.

In the drawing, the numeral 10 designates an elongated cylindrical housing having a bore 11 therein. The bore 11 is screw-threaded at its upper end at 12 while the body 10 is recessed to form a shoulder at its lower end and externally screw-threaded at 10' therebelow.

An adapter 13 is secured by the threads 12 and is in turn secured to the usual string of tubing (not shown). An internal annular shoulder 14 is provided within the bore 11 whereby a reduced bore 15 is formed in the lower end of said body 10.

A hollow sleeve 16 having an outwardly extending annular collar 17 at its upper end is slidably confined within the lower bore 15 by the adapter 13 and a roller-bearing race way 18 at the bottom of said body 10. Said race way being retained by an internally threaded cap 19 which is secured to the body 10 by the threads 10' and is provided with an inwardly extending circular flange 19' which flange engages the race way.

The sleeve 16 is internally threaded to receive the left-hand threads of the upper portion 20 of a nipple 21. A shoulder 22 is formed on the body 55 of the nipple, and a right-hand threaded con-

nection 23 is provided whereby said nipple may be secured to a tool B.

A packing medium 25 is disposed between the shoulder 14 and collar 17, while the sliding fit between the bore 11 and collar 17 is a ground joint.

To prevent the sleeve from rotating during operation, as will hereinafter be explained, ball-bearings 26 are provided in the wall of the body 10. Vertical grooves 27 are formed in the outer periphery of the sleeve 16 and one-half of each ball-bearing 26 protrudes into this groove, said balls being held in position by screws 28. Thus it will be seen that the sleeve is capable of vertical movement but is prohibited from rotation by the balls 26 and grooves 27.

In operation the tool B, such as a packer or the like is set at a desired point, and instead of the weight of the string of tubing resting on the thread connections between the string and tool 20 as is the usual practice, the tubing A is supported by the race way 18.

When it is desired to "take-off" the packer, leaving the same set in the hole, it is only necessary to revolve the member 10 and its cooperating parts. This action will cause the sleeve 16 to revolve with the body 10 due to the balls 26 and grooves 27, thereby disengaging the left-hand threads on the portion 20 of the nipple 21.

As the threads are disengaged the sleeve 16 will be forced upwardly, but at no time is the weight of the tubing on these threads. As all other threads are right-hand threads they will tend to be tightened during the take-off operation. The frictional engagement of the tool B is sufficient to prevent rotation of that member during the take-off operation.

In Figure 4 a slightly modified form of the invention is shown wherein the race way and other structure is disposed on the outside of a string of tubing A.

A collar C connects the string of tubing and confines a race way 30 between itself and a tapered annular member 31 surrounding the tubing. A second collar D forms a seat for the member 31.

A member 32 is rigidly secured to the tubing A, said member being substituted for the sleeve 16, and having grooves 33 in the outer periphery 50 thereof similar to the grooves 27. A member 34 contains balls 35 and grooves 33.

The lower portion of the member 34 is externally, right-hand, screw-threaded at 36 to receive the upper portion of a connecting collar 37, while 65

the lower portion of the collar receives the upper left-hand threads of a tool E.

The tapered member 31 is of sufficient outer diameter whereby said member seats upon the upper portion of the tool E.

The operation of the device disclosed in Figure 4 is principally identical to that form shown in Figures 1-3 and therefore a description of the same is deemed unnecessary.

10 10 From the foregoing it may be seen that a tool simple in construction, cheap in manufacture and positive in action may be had. Also, the forms disclosed may be used not only with well packers but may be employed in combination with all oil 15 field tools.

Manifestly, the construction as shown and described is capable of some modification and such modification as may be construed within the scope and meaning of the appended claims is 20 also considered to be within the spirit and intent of the invention.

What is claimed is:

1. A take-off tool for wells including in combination with a drill pipe assembly, a cylindrical body, a sleeve constrained against other than sliding movement in said body, and provided with a left-hand female threaded socket, a shouldered nipple having a pin receivable in said socket and

a pin on its opposite end for connection to a well tool, a ball race intermediate the lower end of said body and the upper surface of said nipple shoulder and means for retaining said ball race.

2. A take-off tool for wells including a cylindrical body having a ball race secured to its lower end, a sliding sleeve within said body and means having left-hand threaded connections with said sleeve and abutting said ball race for suspending a tool in a well.

3. A tool for releasing special equipment in a well comprising a tubular body, a sleeve therein, means for holding said sleeve against other than sliding movement, a box carried by said sleeve having interior left-hand threads, a bearing race 15 carried by the lower end of said body and means in contact with said bearing race, receivable by said sleeve for connection with said special equipment.

4. A tool for depositing a liner in a well including a tubular body, a sleeve held against other than sliding movement in said body and having an internal threaded box, means receivable in said box for suspending said liner and means for freely supporting the lower end of said body on 25 said latter means preparatory to releasing said tool from said liner.

JAMES G. PHILLIPS.
